A. ELKINS.

ASH SIFTING DEVICE.

APPLICATION FILED JAN. 14, 1919.

1,344,493.

Patented June 22, 1920.

UNITED STATES PATENT OFFICE.

ABRAHAM ELKINS, OF BRIDGEPORT, CONNECTICUT.

ASH-SIFTING DEVICE.

1,344,493.

Specification of Letters Patent. Patented June 22, 1920.

Application filed January 14, 1919. Serial No. 271,026.

To all whom it may concern:

Be it known that I, ABRAHAM ELKINS, a citizen of the United States of America, residing at Bridgeport, in the county of Fairfield and State of Connecticut, have invented new and useful Improvements in Ash-Sifting Devices, of which the following is a specification.

This invention relates to new and useful 10 improvements in ash sifting devices, and pertains more particularly to household devices of this character.

The primary object of the present invention is to provide a device of this character 15 which is neat in appearance, simple in construction and capable of operation by hand.

Referring to the drawings:—

Figure 1 is a transverse sectional view of the device.

Fig. 2 is a detail view of a portion of the device.

Fig. 3, is a longitudinal sectional view of the device.

Fig. 4 is a detail view, and

Fig. 5 is a detail view of a modified form of the invention.

Referring more particularly to the drawings, the reference character 10 designates a box-like receptacle, the top of which is open, 30 and is adapted to be closed by means of the hinged cover 11, which cover is retained in place by means of hinges 12, and is secured in closed position by means of the latches 13.

35 The front wall of the box-like receptacle 10 is partially cut away as at 14 and adapted to be received within said cut away portion is a drawer or the like 15 which is provided with an operating handle 16.

40 Extending longitudinally of the box like receptacle 10 and arranged in spaced relation are two guides or tracks 17, which are circular in cross section and are secured in place by having their ends passed through 45 the end walls of the box 10.

Extending longitudinally of the cover 11 are two guides or tracks 18 which are adapted to overlie the tracks 17, and said guides or tracks are likewise held in place by having their ends secured in the end walls of the cover 11.

50 Mounted for sliding movement on the tracks or guides 17, is a sifting screen, which is provided with side walls 19 and a mesh bottom. The bottom edge of each of the end walls of the sifting member is provided with

guides 20, formed as shown by taking a strip of sheet metal and bending it intermediate of its ends as at 21 to conform in shape to the shape of the tracks or guides 17, and 60 these members 20 form the means for supporting the ash sifting member within the box like structure 10. These members are provided with projecting members 22 perforated as at 23 for the reception of screws or 65 the like by which they may be secured in place.

The top edges of the end walls are cut out as at 24 to receive the curved portion 26 of the metal members 27. These members 27 70 are also provided with projecting portions 28 which are perforated as at 29 to provide means for securing the members 27 in place.

Secured to the front face of the sifting element is a guide 30, and projecting into 75 said guide is a roller 31, which is mounted on a crank arm 32. This crank arm 32 is an integral projection of a shaft 33, mounted for rotation in the bearing 34 in the front wall of the box like structure 10. Mounted 80 in the front wall of the box adjacent the shaft 33 is a second shaft 35 on which is mounted a gear wheel 36, and carried by the shaft 35 is a handle 37, which is rigidly secured to the outer end thereof. 85

Mounted on the outer free end of the shaft 33 is a gear wheel 40 which is adapted to mesh with the gear wheel 36, and receive its rotary movement therefrom.

From the foregoing, it will be apparent 90 that when the handle 37 is rotated the gear wheel 36 will also be rotated which in turn, will serve to rotate the gear wheel 40. Upon rotation of the gear wheel 40 the crank arm 32 will likewise be rotated and will thereby 95 reciprocate the ash sifting element longitudinally of the box like structure 10 to perform the sifting operation.

In Fig. 5, I have shown a construction by means of which the gear wheels 36 and 40 100 are done away with, the ash sifting element being operated directly from the crank.

In this form of the invention, a bearing member 50 is secured in the front wall of the box structure 10 by means of bolts or 105 screws 51, which pass through apertures 52 in an annular flange 53 which is integral with said bearing member 50. Passing through the bearing member 50 is a shaft 54, on the inner end of which is suitably 110 mounted a wheel or the like 56. This wheel 56 is adapted to be received in the guide 30,

and secured to the shaft 54 at its outer end is an operating handle 57. Thus it will be seen that upon rotation of the operating handle 57, the sifting element will be reciprocated longitudinally of the box 10 by means of a direct drive, the gear wheels 36 and 40 being dispensed with.

Having thus described the invention, what is claimed is:

- 10 An ash sifter including a receptacle, having a body portion and a swinging cover, fixed tracks located within said body portion, a removable reciprocating tray located above said tracks and provided with guides adapted to freely slide thereover, a channel bar carried by said tray and arranged verti-
- 15

cally thereon at one side thereof, an actuating means for said tray, said means including a crank having one of its angular branches extending into the channel of said bar, guides on the upper end of said tray, and tracks carried by the cover and received by said last guides when the cover is closed, said last tracks serving to confine the first named guides against said first named tracks 20 and operating to maintain an operative relation between said channel bar and said crank.

In testimony whereof I have affixed my signature.

ABRAHAM ELKINS.
